ARTIFICIAL DENTURE

Jason D. Kinsley, Cedar Rapids, Iowa

Application February 24, 1948, Serial No. 10,394

1 Claim. (Cl. 32—2)

1. My present invention relates to artificial human teeth and more particularly to the occlusal surface thereof and the method by which such surface is produced. The principal objective of my invention is to produce a set of bicuspid and molar teeth which are adapted to form a balanced occlusion. This is established by intraorally milling a set of abrasive bite rims to a perfectly balanced occlusion to serve as a pattern for the occlusal contour of the teeth, whereby to produce a proper relation between the mandibular and maxillary teeth.

In order to produce a perfectly balanced occlusion throughout the entire range of the mandibular function, it is necessary that certain requirements be met. I have found that, by the use of a set of abrasive bite rims wherein the upper and lower rims are of equal width and are correlated when in centric relation, a tilting and rocking action takes place upon the supporting gum ridges during intraoral milling procedure. This is produced by a rotation of the right condyle within the glenoid fossa and a simultaneous downward and forward movement of the left condyle in its path but, when the mandible moves leftward from the centric position, the action is reversed and there is rotation of the left condyle in the glenoid fossa and a simultaneous downward and forward movement of the right condyle in its path, thus shifting the direction of movement. As this shifting takes place, a rocking or tilting of the base plates upon the supporting gum ridges is caused. To overcome this difficulty, I first mill the protrusive curvature and then cut a narrow groove in the upper rim on both the right and left sides along the lines of the lingual bicuspid and molar cusp area. I then fill these grooves with a hard abrasive cement which will not become distorted upon lateral milling. I then carve away the lateral borders from the cement, leaving it in the form of a prominent crest. The case is then placed in the patient's mouth and he is asked to move his jaw laterally toward the right and left. This causes milling in of the lateral concavity and inclination on the lower bite rim. The right and left movements from centric position are separate and independent. By these actions, the left lingual and right buccal slopes are simultaneously milled upon the leftward movement of the mandible, while, upon rightward movement, the right lingual and left buccal are milled. By the operations described, a perfectly balanced occlusion is established, both as to protraction and lateral

movements of the mandible. The case is then keyed in centric and mounted upon an articulator, the cement crest removed from the upper rim and replaced with a layer of heat-softened modeling compound and, with the lower rim cold and wet, the articulator is then closed, thus forming a counterpart of the lower milled occlusal surface in the compound on the upper rim. The lower teeth are then set to correlate with the described counterpart and then the upper teeth are set to articulate with the lower teeth, the teeth being made to simulate the occlusal surfaces of the milled bite rims.

2. In the drawings annexed hereto and forming a part hereof, Fig. 1 shows a cross-section of both upper and lower dentures in centric relation; Fig. 2 shows a mandible moved to one side and in such contact with the upper teeth that there is no rocking of the denture on a gum ridge; Fig. 3 shows the formation of a concavity in the occlusal surface of the lower bite rim during the milling in process; Fig. 4 shows a variation in inclination of the surfaces of occlusion, which variation occurs in some mouths, and in varying degrees, and shows, also, on the right side, the fissures in the lower occlusal surface as being arranged transversely to the movement of the mandible; Fig. 5 shows the form of an occlusal surface of a set of bicuspid and molar upper teeth; Fig. 6 shows the occlusal surface of a set of lower molar and bicuspid teeth with a pair of lines thereon indicating the relative direction of motion of the correlated teeth during mastication; Fig. 7 shows upper and lower correlated teeth with the concavity in the occlusal surface of the lower teeth indicated by dotted lines; Fig. 8 shows a curvature in the occlusal surface of the lower first bicuspid tooth; and Fig. 9 shows a greater curvature surface of occlusion in the third molar area.

Reference will now be made in greater detail to the annexed drawings for a more complete description of this invention. Figs. 1 and 2 show how the dentures are balanced, when properly constructed, to prevent tilting of one by the other, during mastication. When the upper and lower dentures 1 and 2 are constructed, the occlusal surface of the lower teeth 3 has a concave curvature laterally, as well as longitudinally, and the upper contacting area is in the form of a ridge or crest 4, the occlusal surface of the lower teeth 3 being formed in facsimile to the

milled occlusal surface of the lower bite rim 5 and the upper teeth 6 in accordance with the cement crest 7a, as shown in Fig. 3, the upper teeth 6 having a crest or ridge 4 constructed along the line of the lingual cusps which project downwardly into engagement with the lower teeth 3. By a comparison of Figs. 1 and 2, it will be seen that the pressure-bearing surface of the upper teeth is maintained substantially directly in line with the crest of the upper gum ridge so that there is no tendency to cause rocking of the upper denture 1, as would be the case if the area of pressure were outside of the lines *a* and *b*, as in the case of an upper buccal cusp contact. The position of the lower gum ridge is indicated by the lines *c* and *d*, there being a greater span between *c* and *d* than between *a* and *b*, in the average case. From Fig. 1 it is noted that the downward pressure of the upper teeth on the lower is located inside of the lines *c* and *d*. This tends to prevent any rocking of the lower denture 2.

From Fig. 2 it will be noted that the pressure on the lower teeth at one side of the mouth is buccally from the gum crest while, upon the other side of the mouth, the pressure is lingually from the gum crest. Therefore, if there is any tendency by reason of the pressure on the buccal side of the teeth to cause tilting of that denture upon the gum ridge, the pressure on the lingual cusp at the opposite side of the mouth holds the denture down on the gum ridge so that there is no tilting thereof, this being upon the working side which definitely precludes a tilting action. It will also be seen, from, particularly, Figs. 1 and 2, that, whether the teeth are closed in centric position, as in Fig. 1, or are laterally displaced, as in Fig. 2, portions of the upper teeth lie sufficiently outwardly of the contacting ridge portions 4 to prevent the cheek from being drawn in between the upper and lower teeth and bitten thereby, much to the discomfort and injury of the patient.

The bite rims are formed with a slightly greater bite opening than normal. Then, by a protrusive movement of the mandible, a protrusive curvature is milled on the occlusal surfaces of the bite rims 5 and 8, as shown in Fig. 7. Then a narrow groove 7 is cut in the upper rim along the line of the lingual cusps. This groove is then filled with an abrasive cement 7a which is sufficiently rigid to maintain its form throughout the lateral milling procedure. This cement is shown in Fig. 3 at 7a. Next, the bite rim is cut away laterally from the cement, leaving it in the form of a prominent crest. Next, the case is placed in the patient's mouth and, by lateral movement of the mandible, the curvature and inclination are formed, as described above.

The variation in inclination of the occlusal surface of the lower teeth is shown by the lines *e* and *f* in Fig. 4. The attached drawings are merely typical and show some of the variations which may occur as a result of milled registration.

Fig. 5 shows the location of the crest 4 on the occlusal surface in a set of upper molar and bicuspid teeth as being placed lingually from the central line thereof.

Fig. 6 shows the occlusal surface of a set of lower molar and bicuspid teeth having a concavity 3a produced by the described intraoral milling procedure. This surface is provided with engraved fissures on lines transverse to the movement of the mandible on the lingual side, the

direction of which is indicated by the lines *g* and *h*. The food is pressed into these fissures during mastication and, by the action of the upper crest in moving laterally during the act of chewing, the food is crushed and sheared.

Fig. 7 shows the buccal aspect of molar and bicuspid teeth when set in centric relation showing the spacing between the buccal cusps thereof, the dotted line showing the contact of the upper lingual crest area with the occlusal surface of the lower teeth midway between the lateral borders thereof.

Fig. 8 shows the laterally milled occlusal curvature of a lower first bicuspid tooth as being less than that of a lower third molar illustrated in Fig. 9, the line 9 indicating the former and the line 10 indicating the latter, these being illustrative of typical cases. The change in curvature is progressive between these teeth.

In order to make the method clear, the same will now be set out in order. First, casts are made of the jaws to be fitted and then plates are molded over these casts. Next, bite rims are molded on the plates, and then the bite rims are trimmed to approximate the bite opening, although they are left a little oversize in order to have enough material for the milling in which follows next. This consists, at this time, of intraorally milling the protrusive curvature. When this is completed, a groove is cut along the line of the upper lingual molar and bicuspid cusps. When this is completed, the groove is filled flush with abrasive cement which will set hard enough to withstand intraoral milling. The case is then inserted into the patient's mouth and he is instructed to move the mandible laterally, right and left, until the occlusion and concavity have been formed in the lower rim and a balanced occlusion is established.

The case is then mounted on an articulator in centric relation. The cement crest is then removed from the upper plate and replaced with a heat-softened modeling compound, the lower rim being wet and cold. Now, with the modeling compound soft, the articulator is closed, forming a counterpart of the lower rim upon the upper base plate. My lower teeth are made to conform with the upper counterpart, thus producing a replica of the lower milled occlusal surface. Next, my upper teeth are formed with a ridge extending along the area of the lingual cusps. Now, the teeth are set up with the ridge so placed that it, only, can contact the lower teeth, and that at a position substantially midway between the lingual and buccal borders thereof, when in centric relation. The set up teeth now form a replica of the intraorally milled bite-rims. Starting from centric position, it will be observed, from Fig. 2, that upon lateral movement, as the mandible moved rightward, the right upper ridge slides upon the right lingual slopes and, simultaneously therewith, the left upper ridge slides upon the left buccal slopes of the occlusal surfaces of the lower teeth. Similarly, as the mandible moves leftward, the left upper ridge slides upon the left lingual slopes of the occlusal surfaces of the lower teeth and, simultaneously therewith, the right upper ridge slides upon the right buccal slopes of the lower occlusal surfaces.

It is of course understood that the specific description of structure set forth above may be departed from without departing from the spirit of this invention as set forth herein and as defined by the appended claim.

Having now described my invention, I claim:

A denture in which the lower molar and bicuspid teeth have their occlusal surfaces formed as a concavity extending laterally of the mandible, the upper teeth having a longitudinally extending ridge on their grinding surfaces, the lateral curvatures of the concavity being less in the first bicuspid than in the second molar, and the change in curvature being progressive.
